Park, Va.

Application August 23, 1934, Serial No. 741,172

4 Claims. (Cl. 122—155)

This invention relates to heating units or furnaces and more particularly to liquid heating devices.

The invention to be hereinafter described is 5 an improvement over the heating unit described in our co-pending application Serial No. 728,998, filed June 4, 1934.

An object of this invention is to provide a heating unit or furnace adapted for use with hot 10 water or the like, and which is so constructed that it may be readily made out of sheet metal suitably secured together so as to form a jacketed furnace structure which may be used in places where running water is not available.

15 Another object of this invention is to provide a heater of this type which may be used in any room without insulation, the structure of the furnace itself being such that a considerable amount of heat will be radiated therefrom in addition to providing means for furnishing heat 20 at points remote from the heater.

25 A further object of this invention is the provision of a heater having relatively few joints so as to eliminate corrosion and to thereby permit the construction of the heater at a relatively low cost.

A still further object of this invention is to provide a heater of this type which will give free circulation throughout the jacket.

30 A further object of this invention is the construction of a heater of this type which is so constructed that it may be readily converted to oil burning which heating medium will operate very economically with this type of heater.

35 With the foregoing and other objects in view, the invention will be more fully described hereinafter, and will be more particularly pointed out in the claims appended hereto.

In the drawings, wherein like symbols refer 40 to like or corresponding parts throughout the several views,

Figure 1 is a detail front elevation of a heating unit constructed according to an embodiment of this invention.

45 Figure 2 is a detail rear elevation of the heater. Figure 3 is a sectional view taken on the line 3—3 of Fig. 1.

Figure 4 is a detail side elevation of the device.

Figure 5 is a vertical section taken on the 50 line 5—5 of Fig. 1.

Figure 6 is an enlarged vertical sectional view taken transversely of the grate and shaker structure.

Figure 7 is a top plan view of the heater with 55 the smoke chamber removed from the top thereof.

Figure 8 is a top plan view of the smoke chamber.

Figure 9 is a bottom plan view of the smoke chamber.

Figure 10 is a fragmentary enlarged sectional 5 view taken on the line 10—10 of Fig. 7 and showing in detail the manner in which the inner and outer walls of the heater are secured together to prevent bulging or the formation of pockets.

Referring now to the drawings, the numeral 10 10 designates generally the base or lower portion of a heating unit constructed according to an embodiment of this invention. The base member 10 is of jacketed construction and comprises an inner jacket or wall, generally designated as 11, 15 and an outer jacket or wall 12. The two jackets or walls, 11 and 12 are held in spaced relation to each other by means of a plurality of pins or spacer members 13 which may have their opposite ends upset or welded as at 14. This 20 construction is shown in the enlarged sectional view in Fig. 10.

The inner jacket or wall member 11 comprises side plates or members 15 disposed, in the present embodiment, in rearwardly convergent relation. A rear plate or member 17 is secured to the rear edges of the side plates 15, and a front plate or member 18 is secured to the front edges of the plates 15. A bottom plate 19 is secured to the lower edges of the sides 15. 30

The outer jacket or wall member 12 comprises side plates or members 20 disposed in spaced parallel relation to the inner side members 15 and held in such spaced relation by pins or spacer members 13. A rear wall or plate 21 is secured 35 to the rear edges of the sides 20, and a front wall or plate 22 is secured to the front edges of the sides 20. Both the rear and front walls, 21 and 22, respectively, are suitably spaced from the inner rear and front walls 17 and 18, respectively, 40 by means of the spacer members 13. A bottom wall 23 is secured to the sides 20 and to the rear and front walls 21 and 22, respectively.

As will be more particularly noted in Figure 5, the inner bottom member 19 is disposed on an 45 angle to the horizontal, with the rear portion of this member 19 raised, that is, the member 19 is disposed on an upward and rearward inclination, so that hot water disposed between the inner bottom 19 and the outer bottom 23 may freely flow 50 rearwardly and upwardly. It will also be noted from Figure 5 that the upper portions of the rear walls of the inner and outer jackets are disposed on a forward inclination so as to provide a relatively constricted outlet 24 in the top of the 55

- base 10. Intake nipples 25 are secured to the rear wall member 21 adjacent the bottom thereof, and outlet nipples 26 are secured to the upper portion of the rear wall member 21. In the construction of the heater at least two intake and two outlet nipples are provided, although there may, of course, be more or less nipples to which suitable connections may be made to the heating system of the dwelling.
- 10 The front wall of the base 10 may be provided adjacent the bottom thereof with an opening 27, preferably extending from side to side of the heater, the purpose for which will be hereinafter described. This opening 27 provides means by which ashes may be removed from the interior of the furnace, and also provides means by which the grates may be removed or inserted. A hinged door 28 closes the opening 27 and is provided adjacent the bottom thereof with a suitable number of draft openings 29. The passage of air through the openings 29 is controlled by means of a slidable closure 30 mounted on guides 31 carried by the door 28.
- 15 Fuel, where coal, wood, or other relatively solid material is used, may be fed to the interior of the base 10 through a feed opening 32 provided in the base 10 above the lower opening 27. Preferably a chute 33 is secured in this opening 32 and extends outwardly of the outer wall 22 on an upward inclination and is closed by a feed door or closure 34. An opening 35 is provided in the door 34 and a slide or closure 36 is mounted in this opening 35 so as to control the passage of air through the opening 35 when the door 34 is closed, as when the fire is checked or it is desired to reduce the draft through the fuel. The door 34 may be hinged on either its side or lower edge, being shown in the drawings as being hinged at its lower edge, as at 37.
- 20 40 The combustion chamber 38 of the base 10 discharges into a smoke box or jacketed member, generally designated as 38. This smoke box or upper heating member 38 is designed to receive water which is to be heated for domestic purposes, so that the heated gases passing out of the combustion chamber 38 will in turn heat the water within the jacket of the member 38.
- 25 45 The smoke box or upper heating member comprises an inner jacket 39 disposed in spaced relation to an outer jacket 40. The inner jacket 39 comprises side walls 41 disposed in upward convergent relation, a front wall 42 having a substantially vertical upper portion and a downwardly and forwardly inclined lower portion 43, the bottom edge of which meets the upper edge of the front wall member 18. A rear wall 44 having a forwardly extending bottom portion 45 and a vertical portion 46, is secured to the sides 41.
- 50 55 60 The outer jacket 40 comprises outer side walls 47 disposed in spaced relation to the inner side walls 41, a front wall 48, and a rear wall 49 provided at the lower portion thereof with a forwardly extending bottom wall member 50 connecting with the lower edge of the inner wall member 46. Inlet nipples 51 are provided in each side wall 47 and an outlet nipple 52 is provided adjacent the top of the rear wall 49 so that suitable connections may be made to the water system of the dwelling. If desired, however, as shown in dotted lines in Fig. 5, the lower inlet nipples 51 may be connected to the outlet nipples 26 of the base 10 by means of pipe connections 53, so that in this case the smoke box or chamber 38 will act as a superheater for the

water and will also increase the quantity of water which is being heated for the system.

The smoke box or chamber 38 is fastened to the top of the base member 10 by providing outstanding lugs or ears 54 on the bottom of the member 38 which overlie lugs or ears 55 carried by the bottom 10, and fastening devices, such as bolts or rivets 56 pass through these lugs 54 and 55 and hold the two portions of the furnace fixedly together.

10 The top wall 57 of the upper member 38 has an upstanding rim or nipple 58 to receive an end of a smoke pipe or the like for connection to the flue of the chimney.

15 Where solid fuel, such as coal, wood, peat, or the like is to be burned in this furnace an immovable grate member 59 is disposed in the ash-pit, being insertable through the discharge opening 27, and this grate member 59 is preferably held in horizontal position on angle bars or 20 upstanding lugs 60 secured to the inner sides 15. A front or vertical grate member 61 is carried by the grate member 59, this latter member being preferably disposed spaced downwardly from the upper edge of the opening 27, and the vertical 25 grate member 61 substantially covering the opening between the grate member 59 and the upper edge of the opening 27.

30 In order to shake down the ashes resting upon the grate member 59 we have provided a shake structure including angularly related bars 62 which are disposed on the upper side of the grate member 59. A shaft 63 is secured to the central portion of the bars 62 and extends downwardly 35 through a bearing 64 provided in the grate member 59 at substantially the central portion thereof. A shaker handle 65 has one end secured to the lower end of the shaft 63, and the other end projects horizontally out through the lower door 28, projecting through an elongated opening 66 in 40 the door 28. A plate 67 moves with the handle 65 and closes the slot 66 in any position of the handle 65.

45 A damper 68 is rockably mounted on a shaft 69 extending through the upper portion of the upper heating member 38 and regulates the passage of smoke and heat out through the smoke box 38.

50 In the use and operation of the heating unit hereinbefore described, after the connections are made to the heating system and to the domestic water supply system, the fuel may be passed through the feed opening 32. Due to the upward inclination of the inner bottom plate 19 the water will freely flow within the bottom so that this bottom chamber may act as a preheater for the incoming cool water, after which the water passes upwardly between the sides and front and rear walls of the device. The combustible gases will 55 pass upwardly from the combustion chamber 38a to the interior of the smoke box or superheater 38, at which point the water in this member 38 will be heated. Where the member 38 is connected to the base member 10, the hot water 60 passing out through the outlet nipples 26 will flow upwardly through the connecting pipes 53 and into the upper member 38, where the water will be additionally heated and will then flow out through the outlet nipple or nipples 52.

65 70 If desired the upper heating member 38 may be taken off of the base member 10 and inserted in the throat of a fireplace so as to be heated by the fire in the fireplace, and in this position the heating member 38 may be connected to the

heating system so as to act as an adjunct to the heating member 10, or the member 38 may be connected to the domestic water supply system.

It will be apparent from the foregoing that an exceedingly simple hot water heater has been provided, which by reason of its simple construction can be very cheaply constructed, and may be used in a room to be heated, or placed in the basement of the dwelling, at which latter point the outside of the heating unit is preferably covered with insulation to conserve the heat. Also by reason of the inclination of the bottom member 19 of the inner jacket 11, the heating unit may be placed on the same level as the level of the radiators and adequate circulation be provided without the use of pumps or other means to enforce circulation. Preferably the space between the inner and outer jackets of the heater is relatively small, so that there will only be a thin film of water about the combustion chamber and through the bottom, thereby requiring a smaller amount of fuel to heat the water, which by reason of the thin wall of water will be heated to a relatively high degree by a small amount of fuel.

In view of the manner of mounting the fixed grate 59, where it is desired to convert the heater to an oil burner, the grate 59 may be merely lifted from the supporting members 60.

The shaker handle 65 is preferably made in two parts, an inner part 65a and an outer part 65b which telescope one another so that the outer part 65b may be removed when it is desired to open the door 39 to remove ashes or for other purposes.

The lower heating unit 10 may be used with or without the smoke jacket 38, and in like manner the smoke jacket may be used with or without the lower heating unit 10, the smoke jacket being insertable in the throat of a fireplace if desired for the purpose of obtaining hot water for domestic purposes, or as an adjunct to the existing heating system wherein the main heater is positioned in the basement of the dwelling.

It is obvious that various changes and modifications may be made in the details of construction and design of the above specifically described embodiment of this invention without departing from the spirit thereof, such changes and modifications being restricted only by the scope of the annexed claims.

What is claimed is:

1. A heater as set forth comprising a jacketed member constructed of sheet metal or cast iron and having inner and outer walls spaced apart to provide free circulation therebetween, said member also having a flat jacketed bottom provided with an upwardly and rearwardly inclined inner bottom wall to facilitate circulation through the jacketed bottom, said inner bottom wall being inclined in an upward and rearward direction from the front to the rear thereof, the inner and outer walls of the bottom diverging from each other, the rear jacketed wall of said heater being inclined towards the front of the heater from its median line, said heater being open at the top, and a flue structure above said top having jacketed walls, and a damper within the flue structure.

2. A heater as set forth comprising a base member comprising an inner jacket, an outer jacket, means for securing the jackets together in spaced apart relation to provide a relatively thin water

chamber, said inner jacket having a bottom wall upwardly inclined from the front to the end thereof to facilitate circulation, means for discharging fuel into the interior of the inner jacket, means for removing ashes from the lower portion of the inner jacket, and means for supporting fuel in upwardly spaced relation to the bottom of the inner jacket, the inner and outer walls of the bottom diverging from each other, the rear jacketed wall of said heater being inclined towards the front of the heater from its median line, said heater being open at the top, and a flue structure above said top having jacketed walls, and a damper within the flue structure.

3. A heater as set forth comprising a base member including an inner jacket, an outer jacket, each of said jackets being constructed of relatively thin sheet material, means for securing the jackets together in spaced apart relation to provide a relatively thin uniform water chamber, said inner jacket having an upwardly inclined bottom extending from the front to the rear thereof to facilitate free circulation of water in the bottom, a fixed grate member, means whereby said grate member may be inserted or removed from the interior of the base member, means for supporting said grate member within the inner jacket, shaker members disposed above said grate member, means for mounting said shaker members on said grate member for swinging movement, operating means for said shaker members, and a jacketed member extending upwardly from the top of the base member and communicating with the interior thereof, said jacketed member forming with said base member a continuous vertical flue for the products of combustion, the upper part of the rear wall of said base member and the rear uppermost portion of the jacketed member forming an angle with each other.

4. A heater as set forth comprising a base member including an inner jacket, an outer jacket, means for securing the jackets together in spaced apart relation to provide a relatively thin water chamber therebetween, said inner jacket having an upwardly inclined bottom extending from the front to the rear thereof to facilitate free circulation of water in the bottom from the front to the rear thereof, a fixed grate member, means whereby said grate member may be inserted or removed from the interior of the base member, means for supporting said grate member within the inner jacket, radially arranged shaker members disposed above said grate member, means for mounting said shaker members on said grate member for swinging movement, operating means for said shaker members, a jacketed member extending upwardly from the top of the base member and communicating with the upper portion thereof, inlet connections for said base member, outlet connections for said base member, inlet connections for said jacketed member, outlet connections for said jacketed member, and a damper carried by the upper portion of said jacketed member, said jacketed member forming with said base member a continuous vertical flue for the products of combustion, the upper part of the rear wall of said base member and the rear uppermost portion of the jacketed member forming an angle with each other.
